No. 854,461.

PATENTED MAY 21, 1907.

J. C. BURNELL.
ADVERTISING OR OTHER AIR SHIP.
APPLICATION FILED APR. 26, 1906.

UNITED STATES PATENT OFFICE.

JOHN C. BURNELL, OF CHICAGO, ILLINOIS.

ADVERTISING OR OTHER AIR-SHIP.

No. 854,461.

Specification of Letters Patent.

Patented May 21, 1907.

Application filed April 26, 1906. Serial No. 313,792.

To all whom it may concern:

Be it known that I, JOHN C. BURNELL, a citizen of the United States, residing at Chicago, in the county of Cook and State of Illinois, have invented certain new and useful Improvements in Advertising or other Air-Ships, of which the following is a specification.

It has been customary for some time to display advertisements by means of kites adapted to be sailed high above the ground, to the string or line of which the advertisement is attached. This method of hoisting the advertisement is obviously open to the objection that it is only adapted for use on windy days and under circumstances which permit the kite to be raised without interference from buildings, telegraph poles, wires or other obstructions. These objections render the use of kites for advertising purposes unsatisfactory, and very frequently the opportunity to display an advertisement to the gaze of a large assemblage or crowd of people, as, for instance, at foot ball games, horse races, or similar exhibitions, is lost by reason of unfavorable weather conditions. Another disadvantage in the use of kites lies in the fact that it is impossible to raise the kite from localities which are surrounded by buildings or otherwise sheltered from wind on the ground level.

The object of the present invention is to overcome these objections and provide an air-ship or balloon adapted to be raised under all sorts of weather conditions and from localities which would render the use of kites impossible or highly precarious.

The invention relates to the means for securing the gas bag to the framework, to the construction of the framework itself, and to the means for attaching a line or cable in such manner that the balloon or air-ship will be held in horizontal position regardless of the velocity of the wind and of the pull or weight of the line and the advertisement secured thereto.

The invention consists in the features of construction and combination of parts hereinafter described and claimed.

In the drawings Figure 1 is a perspective view of the balloon showing the preferred form of framework; and Figs. 2 and 3 are perspective views of modified forms of framework, the balloon in Figs. 2 and 3 being omitted.

The advertising air-ship of either one of

the forms of construction comprises a gas bag 1 which is preferably of elongated or cigar-shape, which gas bag is firmly secured to a framework of any one of the forms shown. The framework of Fig. 1 consists of upper side rails 2 which serve as a means of attachment for a network of ropes or cords 3 which practically inclose the upper half of the gas bag and extend around and inclose the ends holding the balloon firmly secured to the framework. The framework further consists of lower side rails 4, end rails 5, and cross or brace rails 6 extending in diagonal relation between the side and end rails of the frame. The lower side rails on opposite sides of the framework are connected by means of cross rails 7, which arrangement forms a rectangular framework on three sides, having the ends and top open for the reception and retention of the gas bag which fits down into the open space within the framework, allowing the ends to project outwardly therefrom and allowing the top to rise upwardly from the framework. As shown in Fig. 1 the upper side rails of the framework are placed in a position about midway of the total vertical diameter of the gas bag; or, in other words, at the point of greatest horizontal diameter. This arrangement enables the framework to be rigidly secured to the gas bag by means of the mesh ropes or cords 3 which are secured to the upper side rails.

The air-ship or balloon is secured to a main line or cable 8 which terminates at its upper end in a pair of forward attaching lines 9 which are fixedly secured to the forward ends of the upper side rails, but are held in suitable relation to the lower side rails by means of loops 10 which distribute the pull of the main line to different points as indicated. In addition to the forward attaching lines 9, a center or belly-band 11 is secured to the main line 8, and the belly-band has its end forked to provide center attaching lines 12 which are secured to the lower rails, as indicated in Fig. 1. The rear-end of the framework can be manipulated by means of an adjusting line 13 which, like the other lines, is forked at its rear end 14, and the adjusting line, instead of being fixedly secured to the main line, passes through a loop 15 thereon and is carried down along the main line within reach of the operator, although the loop may be dispensed with under some conditions and the rear line carried down to the ground and anchored separately.

In Fig. 2 is shown a modified style of frame, which, instead of being rectangular, is of V-shape formation, having upper side rails 16 adapted for the attachment of the 5 mesh ropes, and the upper rails are connected with a single lower rail 17 by means of converging end rails 18 which are braced by transversely extending brace rails 19, leaving the upper portion of the framework open, as 10 in Fig. 1, for the reception of the gas bag which is secured in the manner hitherto described. The framework of Fig. 2 is secured in a manner to that hitherto described, except for such variations as are necessary in 15 view of the slightly modified form of construction. The main line 8 terminates in forward attaching lines 20, which, as shown in Fig. 1, are secured to the upper rails, but in place of two lower loops 10 a single loop 21 20 is employed, which, however, is intended to serve the same function. The belly-band 11, instead of being forked at its end, is secured directly to the center of the lower rail, and the adjusting line 13, instead of being forked, 25 is likewise directly secured.

In the construction shown in Fig. 3, the framework is of rectangular form, consisting of side rails 22 and end rails 23. The main line 8 is forked at its end to provide forward 30 attaching lines 24 which are secured directly to the frame, the attaching loops being dispensed with in this case. The belly-band 11 and the adjusting line 13 are exactly like those hitherto described with respect to Fig.

35 1. In use, when the weather is calm, the balloon or air-ship will rise directly from the earth, carrying with it the line having the advertisement secured thereto. The framework being secured to the main line at its forward end, the tendency of the air-ship or balloon will be to tilt up on end more or less by reason of the buoyancy of the rear or unsecured end of the device. It is to correct this 40 tendency that the adjusting line is provided which can be pulled by the operator to bring the gas bag into substantially horizontal position. This tendency of the gas bag to stand on end to a greater or less degree is more apparent in a strong wind than in a calm and 45 it is more especially to correct the tendency to wabble about in a wind that the main line is made fast to the forward end of the frame. If the line were fastened directly to the center of the frame, a strong wind would throw the 50 device entirely out of the control of the operator and the wabbling and diving of the balloon or air-ship, due to the changes in velocity or direction of the currents of air, would tend to shake or wabble the advertising flag 55 or banner, suspended by the main line, to such an extent as to render the advertisement displayed thereon unintelligible. By attaching the main line to the framework in the manner indicated, and by providing an 60 adjustable rear end line, the tendency of the 65

balloon to wabble is reduced to a minimum and the operator is enabled to correct such tendency from time to time as may be necessary by reason of changes in the direction or force of the wind.

The framework of the device can be constructed of light wood or from wire, aluminum, or other suitable material, and it is desirable to employ a gas bag of sufficient size to make it a conspicuous object and one which 70 will be watched with interest by the public, for whose inspection the advertisement is displayed. In view of the fact that the flight of air-ships is of sufficiently rare occurrence to create interest, it is plain that the 75 use of a device of the general shape and appearance of an air-ship will of itself create universal interest which serves to attract the attention of the public to the air-ship itself and to the advertisement carried thereby. 80 The use of kites for advertising purposes is unsatisfactory for the reason that kites are so familiar to the general public that no interest is felt in watching their flight in the air, whereas the reverse is true with respect 85 to the device of the character herein described. The device of the present invention can be used at all times regardless of weather conditions, so that for advertising purposes it will be reliable and thoroughly 90 satisfactory for the purposes intended.

Although the adjusting line has been described as movable independently of the main line, it is not intended to be limited in this respect, since it is possible, under certain 95 conditions, after the lines have been properly adjusted with respect to one another, to make the adjusting line fast to the main line and to operate the device so hitched up. The elongated formation of the gas bag tends to 100 hold the device directly in the teeth of the wind and, by securing the lines substantially in the manner indicated, the air-ship will be held in horizontal stationary position and the 105 wabbling, diving or lateral movements reduced to a minimum.

The device has been described as an advertising air-ship, but it need not of necessity be used for this purpose since, if constructed of suitable size, it may be employed for the purpose of raising passengers, for meteorological or other scientific purposes where a substantially stationary position in the upper air is required.

While in using devices of this general character for advertising purposes the advertisement is usually arranged on a banner or flag attached to the line, it will be understood that in the present case the advertisement could be painted upon the gas bag itself or secured to the framework or displayed in any other suitable manner.

What I regard as new and desire to secure by Letters Patent is:

1. An air ship consisting of an elongated

- gas bag having secured thereto at different points from front to rear a plurality of lines of suitable length to exert the requisite tension to hold and secure the air ship in substantially horizontal position head on to the wind regardless of changes in wind velocity, substantially as described.
2. An air ship consisting of an elongated gas bag having secured thereto at different points from front to rear a main line and an adjusting line, the lines being of suitable length to exert the requisite tension to hold and secure the air ship in substantially horizontal position head on to the wind regardless of changes in wind velocity, substantially as described.
3. An air ship having a main line secured thereto near one end, and having an adjusting line secured thereto near the opposite end for holding and controlling the position of the air ship regardless of wind velocity, substantially as described.
4. An air-ship comprising a gas bag, a framework to which the gas bag is fixedly secured, a main line attached to the forward end of the framework, and an adjusting line attached near the rear end of the framework for holding the gas bag in proper position, substantially as described.
5. An air ship comprising a framework having side rails, and a bottom rail rigidly secured to the side rails, an elongated gas bag secured to the frame between the side rails, and lines secured to the framework and adapted to hold, control and firmly position the air-ship regardless of changes in wind velocity, substantially as described.
6. An air-ship comprising a framework having side rails, and a bottom rail rigidly secured to the side rails, an elongated gas bag secured to the frame between the side rails, a main line secured to the forward end of the framework, and an adjusting line secured to the rear end of the framework for holding, controlling and firmly positioning the air-ship regardless of changes in wind velocity, substantially as described.
7. An air-ship comprising a framework having side rails, and a bottom rail rigidly secured to the side rails, an elongated gas bag secured to the frame between the side rails, a main line forked at its upper end to provide attaching lines secured to the upper side rails, and held in position with respect to the lower side rails by means of a restraining line, and an adjusting line secured near the rear end of the framework for holding, controlling and firmly positioning the air-ship, substantially as described.
8. An air ship for advertising purposes comprising a framework having upper and lower side rails, and cross rails connecting the lower side rails, the framework being open at its ends and top, an elongated gas bag projecting outwardly and upwardly from the framework and rigidly held between the side rails, and lines secured to the framework and adapted to hold, control and firmly position the air-ship regardless of wind velocity, substantially as described.

JOHN C. BURNELL.
